[57] CLAIM

The ornamental design for a desk mounted factory data
collection terminal or similar article, as shown and de-
scribed.

DESCRIPTION

FIG. 1 is a top, front and right side perspective view of
a desk mounted factory data collection terminal or simi-
lar article showing our new design;

FIG. 2 is an enlarged rear elevational view thereof;

FIG. 3 is an enlarged bottom plan view thereof;

FIG. 4 is an enlarged left side elevational view thereof.
